UNITED STATES PATENT OFFICE.

WILLIAM J. KEELEY, OF NEW YORK, N. Y., ASSIGNOR TO THE AUTOPIANO CO., OF NEW YORK,
N. Y., A CORPORATION OF NEW YORK.

TRACKER-BAR AND MUSIC-SHEET MECHANISM.

No. 902,495.

Specification of Letters Patent.

Patented Oct. 27, 1908.

Application filed July 14, 1906, Serial No. 326,190. Renewed August 24, 1908. Serial No. 450,053.

To all whom it may concern:

Be it known that I, WILLIAM J. KEELEY, a citizen of the United States, residing at New York, in the county of New York and State 5 of New York, have invented a new and useful Tracker-Bar and Music-Sheet Mechanism, of which the following is a specification.

My invention relates to music playing instruments and attachments in which a double tracker-bar is provided, or a pair of tracker-bars having two sets of channels of different range.

The principal objects of my invention are to provide means whereby a simultaneous closing of one set of channels and opening of 15 the other can be provided for in such a way that the music sheet can operate from the open one in the usual way, and also to provide for so manipulating the music sheet as 20 to cause it to operate across the surface of the tracker-bar or bars so as to cover either one of the sets of perforations. I have provided for accomplishing these objects in a simple, efficient and convenient manner 25 without the employment of complicated and expensive mechanism.

Reference is to be had to the accompanying drawings, in which,

Figure 1 is a plan of one end of the tracker-bar and music-sheet mechanism showing one form in which my invention may be embodied. Fig. 2 is a longitudinal sectional view of the same, and Fig. 3 is a similar sectional view of a tracker-bar showing a modification.

It has heretofore been proposed to construct a tracker bar with two sets of channels, and to provide means for closing one channel, and independent means for closing 40 the other, the music-sheet ordinarily passing over both sets. It has also been proposed to provide movable tracker-bars for similar purposes.

In order to do away with certain complications which arise under such constructions, and to provide simplicity of operation, and especially to secure the automatic closing of one set of channels when the other is opened, both operations being performed by one motion, I have provided a double tracker-bar, or a pair of tracker-bars with two sets of channels or conduits 10 and 11, one set preferably comprising the ordinary number of channels now used on most instruments of 55 this character, and the other comprising a

large enough number to provide for using all the notes of an ordinary piano. The channels of the first set I preferably connect with the corresponding channels of the opposite set by a series of cross channels 12 in the 60 tracker-bar. There will, of course, be a number of channels of the second or larger set which will not be connected in this way. The passages 12 or the channels 10, as may be desired, are connected by means of ordinary tubes 13, preferably fixed in stationary position with the several primary pneumatics. The tracker-bar 14 in which the channels are located is preferably mounted in stationary 70 position.

The two sets of channels may be connected by a series of stationary tubes 16 extending outside the tracker-bars, these tubes either being connected across from one set of channels directly to the other, or from the tubes 75 13 to the opposite set of channels, as indicated in dotted lines in Fig. 3. In either case the two sets of channels are intended to be alternately opened and closed by means of cap-plates 17 and 18. For the purpose of simultaneously operating these cap-plates by 80 a single motion to open one set of channels and close the other, I have pivotally mounted them on slides 19 mounted to move in guide-ways 20. Each cap-plate is provided 85 with an extension 21 projecting outwardly from its pivot point and operated upon by a spring 22 mounted on the slide. The operation of the spring is to force the cap-plate inwardly, as shown at the left of Fig. 2 to cover 90 the perforations when the slide is in a proper position therefor. When the slide is drawn down as shown on the other side, the spring is contracted and ready to force the cap-plate 95 back into position upon the reciprocation of the slide.

The two slides or other guides for manipulating the cap-plates are preferably operated by the same means to withdraw one when the other is applied. In the construction illustrated I have employed a simple lever 23 for accomplishing this result. This lever is pivoted between the slides and is provided with an adjustable connection with each slide on opposite sides of its pivot, and may also be 100 provided with a handle 24 or other means to enable the operator to manipulate it. It will be observed that the swinging of this lever to its limit in either direction will cause one of the cap-plates to swing over its series of chan- 110

nels, and in the other to move away from them a sufficient distance to permit the music-sheet to be applied to the open set, only one motion being necessary to apply one cap-plate and withdraw the other.

For the purpose of permitting the use of a tracker-bar of the ordinary shape, and in the ordinary position, I have provided means whereby the music-sheet itself, may be manipulated so that in one position of the cap-plates the music-sheet will cover the open channels on one side, while in the other position it may be made to cover the open channels on the other side. For this purpose a pivoted frame 25 is employed. This frame is provided with bearings upon which the two roller shafts 26 are mounted, these shafts passing through the side of the case and working in slots 27 therein. The shafts 26 carry the music-sheet rollers in the ordinary way, and it will be obvious that by the swinging of the frame 25 about its pivot the rolls can be moved from the position shown in full lines to that shown in dotted lines, so as to bring the music-sheet into either of the desired positions.

For the purpose of holding the rollers in either of their adjusted positions a fastening means may be provided. I have shown a stud 28 projecting inwardly from one of the bars 25 and passing through a slot 29 in the case, a thumb-nut 30 being provided for securing the parts in their adjusted positions.

From the description above given the operation of the parts will be readily understood.

While I have illustrated and described a particular form in which I prefer to embody my invention, I am well aware that many modifications may be made therein by any person skilled in the art without departing from the scope of my invention as expressed in the claims. I do not wish, therefore to be limited to the particular construction disclosed, but

What I do claim and desire to secure by Letters-Patent is:—

1. A tracker-bar having two sets of air conducting conduits opening in one face thereof, and a series of connecting channels located entirely within the bar and extending directly from one set of conduits to the other.

2. A tracker-bar having two sets of air conducting conduits opening in one face of the bar, one set containing a larger number of conduits than the other, and a series of channels located entirely within the bar and extending directly from each one of the smaller sets of channels to one of the channels in the larger set.

3. In a music playing device, the combination of a tracker-bar having two sets of tracker-bar conduits, channels entirely within the tracker-bar connecting the conduits of one set with the conduits of the other set, and a single means for simultaneously closing the open ends of one set of conduits and opening those of the other. 65

4. In a music playing device, the combination of two sets of tracker-bar conduits, 70 cap-plates, one for covering each set of conduits, and means connected with both of said cap-plates for simultaneously withdrawing one cap-plate and moving the other cap-plate in position to cover the conduits of one 75 set.

5. In a music playing device, the combination of a plurality of sets of tracker-bar conduits, a corresponding number of cap-plates, and a single means connected with 80 each of said cap plates for simultaneously moving one cap-plate over one set of conduits, and withdrawing another cap-plate from another set of conduits.

6. In a music playing device, the combination of two sets of tracker-bar conduits, a cap-plate for each set, a slide upon which each cap-plate is pivotally mounted; and means for simultaneously moving one slide 85 toward the open ends of the conduits and withdrawing the other therefrom.

7. In a music playing device, the combination of two sets of tracker-bar conduits, a cap-plate for each set, a slide upon which each cap-plate is pivotally mounted, means 95 for simultaneously moving one slide toward the open ends of the conduits and withdrawing the other therefrom, and means for simultaneously swinging the cap-plate which is moved toward the conduits into position 100 over their open ends.

8. In a music playing device, the combination of a tracker-bar having two series of conduits, a pair of cap-plates, one for each series, a pair of slides on which said cap-plates are pivotally mounted, each cap-plate 105 having an arm extending to the rear of its pivot, a pair of springs mounted on said slides for engaging said arms and normally forcing said cap-plates toward the tracker-bar, and a lever pivoted between the slides and connected therewith for simultaneously moving the slides in opposite directions. 110

In testimony whereof I have hereunto set my hand, in the presence of two subscribing 115 witnesses.

WM. J. KEELEY. [L. S.]
